William Novak
INVENTOR
BY Victor J. Evans
ATTORNEY

UNITED STATES PATENT OFFICE.

WILLIAM NOVAK, OF ALLIANCE, OHIO.

COUPLING.

Application filed February 23, 1921. Serial No. 447,188.

To all whom it may concern:

Be it known that I, WILLIAM NOVAK, residing at Alliance, in the county of Stark and State of Ohio, have invented new and useful Improvements in Couplings, of which the following is a specification.

This invention relates to car coupling means, the principal object of the invention being to provide automatic means for connecting two parts together and without the use of pins or other manually operated devices.

A further object is to provide a coupler having spring cushioned elements whereby the shock of one car coming into contact with another is minimized by the cushion element interposed.

A further object is to provide means whereby the cars may be operated upon a curve without binding or straining the connecting elements.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a top plan view showing a car coupler made in accordance with the invention.

Figure 2 is a side elevational view thereof, parts being broken away in order to disclose the construction.

Figure 3 is a plan view illustrating the application of the invention.

Figure 4 is a transverse sectional view taken on line 4—4 of Figure 2, and

Figure 5 is a similar transverse sectional view taken on line 5—5 of Figure 2.

Referring to the drawings in detail, the numerals 10 and 11 represent, respectively, two cars such as are used upon railways.

Connected below the flooring with the understructure of the car 11, is a beam 14, carrying at its outer end a pin 15 on which is pivotally mounted the forked ends 16 of a convexly curved head 17, having formed in its opposite sides transverse recesses 18,

the purpose of which will be further on described.

Similarly attached below the car body 10 is another beam, comprised of an upper plate 20, and a lower plate 21, having openings 22, by which the plates are secured in rigid engagement with the understructure of the car, the front portion of the lower plate 21 being bent down into a vertical element 23 and then outwardly into an extension 24, parallel with, but spaced from the upper plate 20.

A reinforcing bracket 25 is secured by bolts 26 immediately rearward and adjacent to the angular element 23, the bracket being so formed as to act as a brace.

A rectangular block 27 is freely slidable between the upper and lower plates 21 and 24, and set in its rear end is a rod 28, the same pressing through a suitable opening formed in the element 23 and is encircled by the coils of a strong compression spring 29, one end of which abuts against the block 27, while the opposite end of the spring makes contact with the vertical element 23, the effect being to normally press the block outward.

In order to lighten the block 26, a central longitudinal opening 30 is formed from end to end therethrough, except at the point of insertion of the rod 28.

Formed through the plates 20 and 24, respectively, are slots 31 and 32, receptive of a bolt-like bar 33, having an oblong cross section which passes upward through an opening 34 formed in the block 27, this bar having an enlarged extending head 35 at one end, and is drilled to receive a cotter pin 36 at the upper extending end by which the bar 33 is held in position. This bar 33 and the slots 31 and 32 act to limit the sliding movement of the block 26.

At the outer end of the coupler block 26 is formed an enlarged head 37, having an arm 38 and a projecting part 39 thereon, the arm 38 having an inwardly extending projection 40.

Extending laterally to one side of the block 26, is a bracket 41 carrying a pin 42, on which is pivoted a lever, the short end 43 of which is normally pressed outward from the block 26 by a bent flat spring 44 secured to the side of the block. The outwardly extending arm 45 is pressed tightly against the

projecting part 39, and is formed with a hooked end 46 having a cam-like surface 47 disposed slightly in advance of the hook 40 with which it is oppositely disposed.

- 5 In operation, the head 17, attached to the car which it is desired to effect the coupling, makes contact with the hooks 40 and 46 substantially simultaneously, causing the hook 40 to engage in one of the recesses 18, where-
10 upon the hook 46 is engaged in the oppositely disposed recess due to the effect of the spring 44, while the outer extremity of the pivoted head 17 is suited to be received within the head 37, which being pressed forward by the spring 29 effectually locks the cars together.

When it is desired to uncouple the cars the lever end 43 is pressed inward and the head 17 is swung out from the recess in the head 37, allowing the cars to separate in an obvious manner.

By means of the pivotal connection between bar 14 and the head 17 the cars may take curves without binding or straining the connecting elements.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In a car coupler, a hollow beam consisting of a pair of plates connected together, one plate having an intermediate portion extending at right angles to the other portions so that the front portion of said plate is spaced from the front portion of the second plate, 40 a block slidably located in said space, a guiding bar for the block supported by the right-angled part of the plate, a spring on said bar engaging the rightangular portion and the end of the block, means for limiting the 45 sliding movement of said block and a coupling head carried by the block.

In testimony whereof I affix my signature.

WILLIAM NOVAK.
